(57) **CLAIM**

The ornamental design for charger for electric vehicle, as shown and described.

DESCRIPTION

FIG. 1 is a perspective view of charger for electric vehicle, showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is an enlarged view of a portion of FIG. 1;

FIG. 9 is an enlarged view of a portion of FIG. 1;

FIG. 10 is an enlarged view of a portion of FIG. 2;

FIG. 11 is an enlarged view of a portion of FIG. 4;

FIG. 12 is an enlarged view of a portion of FIG. 4;

FIG. 13 is an enlarged view of a portion of FIG. 4;

FIG. 14 is an enlarged view of a portion of FIG. 5;

FIG. 15 is an enlarged view of a portion of FIG. 5;

FIG. 16 is an enlarged view of a portion of FIG. 5;

FIG. 17 is an enlarged view of a portion of FIG. 6; and,

FIG. 18 is an enlarged view of a portion of FIG. 6.

The broken lines in the drawings show portions of the charger for electric vehicle that form no part of the claimed design. The dash-dot lines in FIGS. 1-2 and 4-6 showing boundaries of enlarged views do not form any part of the claimed design.

1 Claim, 17 Drawing Sheets
